* cited by examiner

Primary Examiner — Deanna L Pratt(74) *Attorney, Agent, or Firm* — IP Investment Law Group(57) **CLAIM**

We claim the ornamental design for the display with graphical user interface, as shown and described.

DESCRIPTION

The single FIGURE is a front view of the display with graphical user interface. The broken lines in the drawings illustrate portions of the display with graphical user interface that form no part of the claimed design.

1 Claim, 1 Drawing Sheet
